CLAIM

The ornamental design for a power supply, as shown and described.

DESCRIPTION

FIG. 1 is perspective view of a power supply showing my new design;

FIG. 2 is an alternate perspective view thereof;

FIG. 3 is a rear view thereof;

FIG. 4 is a front view thereof;

FIG. 5 is a side view thereof (the opposite side view being identical);

FIG. 6 is a top plan view thereof; and,

FIG. 7 is a bottom view thereof.

The even dashed lines show environment and form no part of the claimed design.
